UNITED STATES PATENT OFFICE.

EMORY S. LEWIS, OF NEW YORK, N. Y.

DESIGN FOR A LIGHTING-FIXTURE SHELL.

Application filed March 12, 1924. Serial No. 8,911. Term of patent 7 years.

To all whom it may concern:

Be it known that I, EMORY S. LEWIS, a citizen of the United States, and a resident of the county of Kings and city and State of New York, have invented a new, original, and ornamental Design for a Lighting-Fixture Shell, of which the following is a specification, reference being had to the accompanying drawing, forming a part hereof.

Fig. 1 is a side elevation of the shell, with parts in section, and

Fig. 2 is an inverted plan view showing a portion of the shell in full lines, it being

understood that the surface ornamentation is circumferentially continuous.

The shell is characterized by a grille, or fretwork, 10 surrounding and slightly above the lamp openings 11.

I claim:

The ornamental design for a lighting fixture shell, substantially as shown and described.

EMORY S. LEWIS.
